A. Bitner

United States Patent Office.

ABRAHAM BITNER, JR., OF LANCASTER, PENNSYLVANIA.

Letters Patent No. 97,753, dated December 14, 1869.

IMPROVED ADJUSTABLE WAGON-BOTTOM AND CHUTE.

The Schedule referred to in these Letters Patent and making part of the same

To all whom it may concern:

Be it known that I, ABRAHAM BITNER, JR., of the city of Lancaster, in the State of Pennsylvania, have invented a new and improved Combination on Wagons or Vehicles for hauling merchandise, lumber, or coal, especially adapted for the latter purpose; and I do hereby declare that the following is a full, clear, and exact description of the construction of the same, reference being had to the accompanying drawings, making a part of this specification, in which—

Figure 1 is a perspective view of an ordinary wagon-body with my improvements.

Figure 2, an outline side elevation of the wagon and extension-chute in place.

The nature of my invention consists in adapting an ordinary wagon to the especial purpose of delivering lumber or coal, and prevent the necessity of scrubbing the sidewalk, after delivering coal, which is directly dropped through the grate to the cellar from the wagon, without rehandling, by means of an adjustable inclined bottom trap fixed, and portable chute-attachment.

To enable others skilled in the art to make and use my invention, a brief description will be sufficient.

Figure 1 represents a wagon-body, A, in common use, with three side-posts, E, perforated for a headed bolt-rod, e, to support the inclined bottom B, made of boiler-iron, or wood lined with heavy sheet-iron.

The end-gate is provided with a sliding door, D, opening into an attached chute, C.

This attached chute is provided with rack-teeth or notches, for the reception of the rod or iron brace f, over the front end of a portable chute, F, so as to extend from the curb, across the pavement, to the grate or place of discharge into the vault or cellar; is also made of boiler-iron, or its equivalent.

The side-pieces E are united across the bottom of the box, and the forward end sufficiently inclined outward, so that when the burrs are removed from the end of the headed bolts e, the bottom B will drop down in front, on the lower fixed supports of the side-pieces E, and convert the box for hauling any kind of merchandise.

I am aware that fixed inclined bottoms are used for

hauling lumber, so that the ends, projecting, come over the horse or horses, and therefore claim no novelty, either as a wagon for hauling merchandise or lumber.

My invention consists in adapting the same vehicle to these several purposes, and more especially to the delivery of coal, for which purpose the sliding door could be made in the hind end of the adjustable bottom, instead of the end-gate, which latter is preferable.

This arrangement affords great facilities to forwarding-merchants, who alternately require the use of their wagon for the one or the other purpose, when coal and lumber are kept for sale, as in most cases. Instead of having wagons for each special use, or in the absence of such, even where they have them, on an emergency, this arrangement will accommodate either purpose, with little trouble to make the desired change.

The soiling of the sidewalks, with coal-dust and coal, the shovelling out, the backing over the curb, and much loss of time, to say nothing of the labor, are remedied by means of the portable chute, which is speedily attached, and as readily disconnected, and thrown upon the wagon.

I am fully aware that this arrangement is simple, and may seem to lack novelty, when each part is separately considered, but its utility is fully tested, and its importance established, as a labor-saving invention or combination; nor am I aware that such an arrangement has ever before been in use, or anything substantially like it, as a whole; I therefore do not claim the parts separately considered.

What I claim as my invention, and desire to secure by Letters Patent, is—

The arrangement of the adjustable bottom B, in a wagon, in combination with a trap or valve, D, in said bottom, so that it may be connected with a trough or chute, for discharging coal or the like, in the manner and for the purpose specified.

A. BITNER, JR.
